UNITED STATES PATENT OFFICE

JOHN J. GILSENAN, OF NEWARK, NEW JERSEY

DESIGN FOR A WATER CURTAIN NOZZLE

Application filed December 12, 1930. Serial No. 37,952. Term of patent 14 years.

To all whom it may concern:

Be it known that I, JOHN J. GILSENAN, a citizen of the United States, residing at Newark, in the county of Essex and State of New Jersey, have invented a new, original, and ornamental Design for Water Curtain Nozzle, of which the following is a specification, reference being had to the accompanying drawings, forming part thereof.

Figure 1 is a rear view of the water curtain nozzle showing my new design, and Figure 2 is a side view thereof. Figure 3 is a front view.

I claim:

The ornamental design for a water curtain nozzle as shown.

JOHN J. GILSENAN.
